UNITED STATES PATENT OFFICE.

CHARLES E. LEE, OF CHICAGO, ILLINOIS, ASSIGNOR TO ELECTRIC GOODS MANF'G COMPANY,
OF BOSTON, MASSACHUSETTS, A CORPORATION OF MAINE.

INTERCOMMUNICATING TELEPHONE.

No. 866,794.

Specification of Letters Patent.

Patented Sept. 24, 1907.

Application filed February 28, 1906. Serial No. 303,375.

To all whom it may concern:

Be it known that I, CHARLES E. LEE, a citizen of the United States, and a resident of Chicago, county of Cook, and State of Illinois, have invented a new and useful Improvement in Intercommunicating Telephones, of which the following is a specification.

The main purpose of my invention is to avoid the necessity in intercommunicating telephones of returning the switch-bar or switch-plug to the home connection or position.

My invention consists in so combining and adapting and connecting certain springs with the switch-bar and its connecting terminal points at each intercommunicating station as to obtain the above result.

15 My invention will be plain from the drawings, in which

Figure 1 is a diagrammatic plan of so much of an entire apparatus as is necessary here; Figs. 2, 3, 4 and 5 are plans showing the different positions of the springs 20 and push-button. Figs. 6 and 7 are modifications.

I have not shown the circuits, as those will be readily understood.

I will now describe my invention, referring to said drawings.

25 X is a telephone hanging upon the telephone-hook A which extends beyond its pivotal point into a latch a.

D is a spring of the usual switch-hook combination shown merely to indicate how latch a is depressed on removal of telephone.

30 1, 2, 3 and 4 are springs, of which spring 1 is connected with a circuit which extends by wire y to switch-arm B which is in movable connection with points 1 to 11, which connect with circuit wires extending to that number or any desired number of distant stations to be similarly constructed. Spring 2 is in connection with the talking mechanism; spring 3 with the home or station circuit-wire; spring 4 is the terminal of the battery which rings the bell.

35 In Fig. 1 and Fig. 2, the push-button C, the latch a and the springs 1, 2, 3 and 4 are shown in normal position, the telephone being upon the hook A and its latch portion a being thus out of contact with any of springs 1, 2, 3 and 4.

In Fig. 3, the receiver has been removed from the 45 hook A which has allowed its latch-end a to fall behind spring 2, and in position to engage spring 1.

In Fig. 4, the push-button C has been pressed and spring 1 has slipped by the latch a, slightly elevating the same in passing, which latch has again sprung 50 down to catch spring 1 and said push-button in pushing.

Spring 1 has, by means of pin 5 thereon, pushed against insulator 6 on spring 3, and so pushed spring 3 away from talking-circuit spring 2 and brought spring 2 into contact with switch-arm spring 1, which position 55 is then locked by the latch a and thus establishes elec-

tric connection through wire y with switch-arm B and so potentially to any one of the points 1 to 11 according to the position of the switch B.

In Fig. 5, by means of further or a second pressure upon the push-button C, the switch-arm spring 1 brings 60 spring 2 in contact with the ringing spring 4 which, through switch B, is thus brought in circuit with the bell of any desired station, thereby calling such station.

Upon removing pressure from the push-button, the 65 talking proceeds. When the talking is ended, the telephone being hung on the hook A interrupts the circuit so established by releasing spring 1 from engagement with latch a and so returns the springs to the position of Figs. 1 and 2.

In Figs. 6 and 7, I show a possible construction, 70 using only three springs, in this case the latch a takes the place of spring 2, and is permanently connected with the talking mechanism, and so adjusted that when the latch a is in normal position with the receiver on the hook A, as shown in Fig. 6, a circuit is established 75 between spring 3 and the latch a, giving the same result as in Figs. 1, 2 and 3, where the springs 2 and 3 are in contact. Upon pressing the button C, the spring 3 is pushed away from contact with latch a by the action pin 5 of spring 1 pressing against the insulated 80 piece on spring 3, and in its place spring 1 is held by latch a and makes contact through the same to the talking mechanism; thus it will be seen that Fig. 6 shows a condition to give the same results as are obtained in Fig. 3, while Fig. 7 shows the same results 85 as are obtained in Fig. 4. The final push of the button brings spring 1 in contact with spring 4, thus ringing the bell as in the case where four springs are used.

Having described my invention, what I claim is:—

1. In intercommunicating telephone devices, the combination with the pivot telephone-hook A of an extension thereof beyond the pivot forming a latch a thereon, a circuit-connecting mechanism controllable by said latch, a push-button controlling the relations of said latch with the circuit-connecting mechanism aforesaid, and, a circuit-connecting mechanism or switch for connecting with any desired number of terminal points; substantially as described and shown. 90

2. In intercommunicating telephone devices, the combination of a push-button, circuit-springs properly arranged in relation thereto, a telephone-hook properly pivoted and extending into a latch so arranged that the weight of the telephone upon the hook will hold the latch apart from any of said springs, means for depressing latch a on removal of telephone, a switch-arm and any desired number of terminal points, and a wire y connecting one of said springs with said switch-arm and terminal points; substantially as described and shown. 95

In witness whereof, I hereunto subscribe my name this 27th day of February, 1906.

CHARLES E. LEE.
